THREAD CLEARER

Samuel Hyslop, Newton, Mass.

Application December 8, 1934, Serial No. 756,636

4 Claims. (Cl. 28—68)

This invention relates generally to winding machines, and more particularly it aims to provide a novel and improved thread clearer for silk, rayon and other threads, and having the advantages and improvements hereinafter described.

In the drawing of the embodiment of my invention selected for illustration and description herein:

- 10 Fig. 1 is a perspective view of the same;
 Fig. 2, a front view;
 Fig. 3, a plan of the clearer plate;
 Fig. 4, a side or edge view of the same; and
 Fig. 5 shows the relative arrangement of the
- 15 several parts preparatory to assembling and uniting them to form the thread clearer member.

Referring first to Fig. 1, my novel clearer comprises a base 1, of suitable size and material, as metal, having, on its rear face, a horizontal channel 2, adapted to receive any convenient member, as the traverse rod, not shown, on the winding machine, and to which it is secured by any suitable means, as a screw 3, extended through a flange 4 on the base, and against the rod referred to.

At the top and bottom, respectively, of the base, it is provided with thread guides 5, 6, of suitable construction, to guide the thread 7 to and from the clearer plate 8.

30 The purpose of the clearer plate of course is to remove from the thread, so far as possible, slubs, knots, snarls and waste of any kind, as the thread passes through the clearer, as, if that is not done, the pull resulting from a large knot or 35 snarl striking the plate will break the thread, and then the operator must remove the imperfection, retie the thread, and thus prevent the stub or snarl from remaining in the thread, and going into the fabric.

40 To effect the above end, the novel plate 8 is provided. The outer end of the plate is forked at 9, 10, to receive the thread 7, as the operator grasps it and guides it into and through the guide 5, forked plate arms 9, 10, and guide 6.

45 The clearer slot 11 may be as narrow as desired to receive the very fine threads now used, and the width of the slot may be made by my novel method hereinafter described of any measurable width, as from 1/1000 of an inch up. Preferably 50 the slot is increased in width at points, as pointed out later.

It is a matter of common knowledge with those skilled in the art that, as the thread passes through the slot of the clearer plate, the contact 55 of the thread with the sides of the slot which,

as usually made is rough, acts to scrape and disturb the thread surface and create a "fuzz", or fly waste, as it is called, of the thread material, and of an oily, greasy or waxy nature, if the thread is of rayon, silk or wool, which material forms part of the fly waste, thrown off by the thread as it travels through the clearer.

Some of this fly waste collects on the plate surface adjacent the slot 11, and some of it is thrown inwardly toward the inner end of the slot 11, and accumulates or builds up on the edges at the end of the slot 11, back of the path of travel of the thread.

To accommodate this built up mass of lint, it has been customary to provide an opening at the 15 inner end of the slot corresponding to the slot 11; but that, in turn, is gradually closed by the continued lint building up process, and it is customary for the operative to periodically push the thread rearwardly by the end of the finger as the 20 thread travels, and in that way, crowd the lint or waste out of the opening referred to, part of the lint or waste going, perhaps, with the thread into the fabric, some of the balance dropping through the opening to the floor, and some ad- 25 hhering to the plate.

I have discovered that, if a suitable opening, both in size and shape, is provided at the rear end of the slot 11, the accumulated mass of fly waste will usually take care of itself. To meet 30 this difficulty successfully, I provide at the inner end of the slot 11 a slot or pocket 13 progressively larger, both as to the width and length, and with no dead end, so to speak.

Referring to Figs. 1 and 3, there is provided 35 the enlarged slot 13, into which the slot 11 opens, and this in turn opens into a still larger pocket portion 15. Now, as the waste is thrown off the thread toward the slot 13, the waste collects on the walls or edges of the slot, and in due time 40 the built up waste mass will usually drop off and free itself. If, however, it should fail to do so sufficiently to keep the slot 13 fairly free, then as the waste builds up in the slot 13, it will build up rearwardly toward the slot 15, and in due time 45 will drop through the slot 15, there being no dead end to the slot 15 to retard the free passage of the waste material through that slot.

To provide this slot 15 with no dead end, the rear end of the plate 8 is offset upwardly, or the lower face is undercut or channeled, as at 14, to the extent that the face of the undercut section is slightly above the plane of the upper face of the plate 8. The plate has an upwardly extended flange 16, seated in a channel 17 on the front of 50 55

the base 1, and where the plate 8 may be secured by any suitable means, as a screw 18.

Furthermore, the upper face 19 of the plate 8, and also the lower face 20 if desired, are made sloping from the slot 11 laterally to the opposite side edges 21, 22, of the plate to facilitate the sliding away from the slot, so far as possible, of some of the light waste before it becomes mixed with the wax and grease, or oil. Experience has proven that this material is so light that the incline referred to helps it to free itself from the heavier wax and grease. The faces 19 and 20 are polished.

To avoid the creation of the fly waste to a large extent, the faces of the plates forming the slots 11, 13, 15, and the edges of the forked arms 9, 10, are ground and polished, as distinguished from such slots that are now merely sawed in the plate, and necessarily left unpolished, and thus the former really are smooth edges that substantially reduce the wear of the threads in passing over them.

It is very desirable to provide a thread clearer with a slot of proper size to clear a thread of from 1/1000 to 3/1000 of an inch in width, which is now much used.

To provide a plate with a slot of a thickness of from 1/1000 of an inch up to a width sufficient to enable a polishing element to be used has not been practicable, but I provide such slot as follows:—

I make two plate members 23, 24, Fig. 5, either by making them separately, or by making a plate member 8, Fig. 3, and cutting it lengthwise along the center line, and grind and polish the edges. I then assemble the members 23, 24, in Fig. 5, with a spacer of suitable material 25, as metal, between their opposed edges, of a thickness to provide the completed plate with a slot of desired width, and fuse or weld the rear ends of the pieces together.

Thereafter, the portion of the spacer forward of the flange 16 is broken out.

My invention is the most efficient device of its kind I know of, and is not restricted to the precise embodiment thereof described and illustrated herein.

I claim:

1. A thread clearer comprising a base member having means to secure it to a support; and a clearing plate member with a thread clearing slot, having open ends and a pocket between the ends, and an offset flanged portion at its inner end of the plate supporting the slotted member and secured to the base. 5 10

2. A thread clearer comprising a base having means to secure it to a support, and a clearing plate member thereon with a thread clearing slot 15 having open ends and a pocket between the ends, and a transverse undercut flange on the rear end of the plate member securing it to the base leaving an unobstructed fly-waste removing slot and pocket from end to end of the plate to permit the 20 fly-waste to remove itself.

3. A thread clearer comprising a base having means to secure it to a support, and a clearing plate on the base with a continuous slot there-through longitudinally with a progressively expanding fly-waste removing pocket in the slot, and an undercut flange portion on the plate rear end supporting the plate on the base and leaving an unobstructed fly-waste removing pocket and slot from end to end of the plate to permit the 30 fly-waste to remove itself. 23

4. A thread clearer comprising a body, a clearing plate thereon with a thickened rear end undercut transversely, a longitudinal slot the length of the plate with a pocket therein between the slot 35 ends, the pocket terminating approximately at the thickened plate section, thus providing an endless fly-waste freeing slot with a clear area of the offset plate lower face between the slot and the nearest obstructing wall. 40
